DOMESTIC APPLIANCE

William C. Crimmins, Van Buren, Ind., assignor
to General Motors Corporation, Dayton, Ohio, a
corporation of Delaware

Application June 2, 1948, Serial No. 30,595

5 Claims. (Cl. 161—1)

1

This invention relates to a domestic appliance and more particularly to a movable control having a shifting holding station.

It is an object of my invention to provide a simple, reliable, inexpensive mechanism which will provide a resilient holding station at one point in one direction of movement without any holding at that point in the return movement.

It is another object of my invention to provide a simple, reliable, inexpensive mechanism providing a resilient holding station at one point in one direction of movement and transferring the said holding station to a second point in the return direction of movement.

It is another object of my invention to provide a simple, reliable, inexpensive mechanism providing a resilient holding station which is reset to another position by the continuance of the movement of a control.

To attain these objects I provide a set of cam-operated control devices adapted to be operated in one direction by a knob and in the return direction by a spring-wound clock mechanism. A primary detent is provided on the operating shaft having a projection capable of entering a notch in a second rockable detent which is resiliently held in either of two positions. The two positions of the secondary detent are arranged so that the notch can be entered on one side in one direction of movement and from the opposite side in a second direction of movement. When the projection strikes the far side of the notch the second detent is turned to the second position so that upon the return movement, the projection can freely enter the notch and engage the far side.

Further objects and advantages of the present invention will be apparent from the following description, reference being had to the accompanying drawing, wherein a preferred form of the present invention is clearly shown.

In the drawings:

Fig. 1 is a view, partly diagrammatic, disclosing in the off position the control devices and the detent mechanism embodying one form of my invention;

Fig. 2 is a view similar to Fig. 1 disclosing in the simmer heat position the control devices and the detent mechanism;

Fig. 3 is a view similar to Figs. 1 and 2 disclosing in one of the high heat positions the control device and the detent mechanism; and

Fig. 4 is a vertical sectional view through the structural embodiment of the control device and detent mechanism.

Referring now to the drawings and more par-

2

ticularly to Fig. 1, there is shown a control knob 20 adapted to cooperate with a pointer 22. This control knob is mounted upon the front end of an operating shaft 24 indicated in the diagrammatic views by a dot and dash line. This operating shaft 24 has a wide flat on one side and a bead on the flat on the opposite side so that the primary detent member 26 and the operating members 28, 30, 32 and 34 may be properly assembled on the shaft in the correct orientation with the control knob 20.

At the far end of the operating shaft 24 there is provided a clock mechanism 36 of the spring-wound type wherein, when the shaft is turned in a clockwise direction the clock spring is wound and when the control knob 20 is released there is a tendency for the spring to unwind and drive the operating shaft 24 and the control knob 20 in a counterclockwise direction at a uniform rate of speed. A friction spring clutch is also provided between the clock mechanism 36 and the operating shaft to make it possible for the control knob 20 and the operating shaft 24 to be turned in either direction manually without damaging the clock mechanism. A friction spring clutch of a type suitable for use in this device is illustrated in the Rhodes Patent 2,434,471 issued Jan. 13, 1948.

My invention is applicable to control devices 30 of various types, such as the switches and the valves. For the purpose of illustrating my invention I have shown control devices in the form of switch mechanisms connected for the control of a two-element electrical heating unit such as 35 might be used for a deep well cooker in an electric range. For example, there is illustrated a heating unit 38 having a rating of 800 watts upon a voltage of 235 volts, and a second heating unit 40 having a rate of 500 watts at 117 volts.

40 The adjacent terminals of these heating units 38 and 40 are connected to the movable reed element 42 of a double-throw switch mechanism which includes stationary contacts 44 and 46. The movable element 42 is moved into engagement 45 with either of these stationary contacts 44 and 46 or out of engagement with both contacts by the cam 32. The opposite end of the heating unit 38 is connected to the movable reed element 48 operated by the cam 34 into and out of engagement with the stationary contact 50. The remaining terminal of the heating unit 40 is connected to the movable reed element 52 having contacts at its lower end cooperating with the stationary contacts 54 and 56.

55 The movable reed element 52 is operated by

the cam 28 into engagement with either of the stationary contacts 54 or 56 or out of engagement with both contacts, as is shown in Fig. 1. An additional movable reed element 58 is provided having a contact at its lower end adapted to engage the stationary contact 60. It is operated by the cam 30. The movable reed element 58 is connected to an indicating light 62 which in turn is connected by the conductor 64 with the neutral (N) supply conductor 66. The stationary contacts 50 and 60 are connected to the conductor 68 which connects to the supply conductor 70 which is also marked L₂. The stationary contacts 44 and 54 are both connected to a conductor 72 which connects to the supply conductor 74 also designated L₁. The stationary contacts 46 and 56 are connected to a conductor 76 which in turn connect with the neutral conductor 66, also marked N.

With this cam arrangement the control knob 20 can be turned to any one of the positions indicated to obtain various heating rates. In the "medium high" position, both heating units 38 and 40 are connected in series across the supply conductors 74 and 70 which have a potential of 235 volts. In the "low" position, the heating unit 38 alone is connected across the supply conductors 66 (N) and 70 (L₂) having a rated voltage of 117. In the "simmer" position illustrated in Fig. 2 both heating units are connected in series across the conductors 66 (N) and 70 (L₂) while in the "high" position illustrated in Fig. 3 the heating unit 38 is connected across supply conductors 70 (L₂) and 74 (L₁) while the heating unit 40 is connected across the supply conductors 70 (L₂) and 66 (N).

It is desired to provide a stationing means which will hold the operating shaft 24 when it is turned manually to either the "medium high," "low" or "simmer" positions. It is also desired to provide resilient opposition to the movement of the control knob when it is moved from the "simmer" position to any one of the "high" positions. It will be seen that the "high" positions are graduated up to 20. These legends are in accordance with the time required to return the shaft 24 to the "simmer" position at the uniform speed at which the shaft is driven by the clock mechanism when turned to the various "high" positions. The clock mechanism will turn the control knob from the 20 minute mark to the zero mark indicated by the arrow in approximately 20 minutes and because of the uniform speed, other positions will be proportionate. Although it is desirable to provide a resilient detent means requiring forcible movement when passing from the "simmer" to the "high" positions, it is desired that in the reverse direction no resistance be provided so that the spring-driven clock mechanism can drive the shaft directly into the same position at the end of the period of time for which the knob 20 is set.

To accomplish this, the operating shaft 24 is provided with the primary detent member 26 as shown. This primary detent member 26 has a projection 80 shown in Fig. 1 as resting against a roller 82 mounted upon the detent arm 84 which is pivoted upon the pin 86 to a portion of the housing of the control. The tension coil spring 88 extends between the spring stud 90 upon the opposite end of the detent arm 84 and the stop stud 92 fixed to a portion of the structure of the case. To turn the control knob 20 from the "off" to the "medium high" position, the projection 80 must lift the roller 82 out of the way against the

tension of the spring 88 until the roller 82 drops into the notch 94 which will hold it in that position. To get from the "medium high" to the "low" position, there is provided a second projection 96 which must lift the roller 82 until it can drop into the notch 98. To get from the "low" position into the "simmer" position, a third projection 100 is provided which must lift the roller 82 out of the way to make the change of positions.

This simple arrangement will not suffice for providing the desired detent between the "simmer" and the "high" positions. Therefore I have provided a second detent or stationing system including an additional projection 123 upon the opposite side of the detent 26. This additional projection 123 is adapted to engage projection 125 upon the secondary detent 127 pivoted upon the pin 129. This engagement is clearly disclosed in Fig. 2. This secondary detent 127 is also provided with a notch 131 large enough to receive the projection 123. The secondary detent 127 is resiliently held in this position by a notch 133 which in Fig. 2 receives a complementary projection 135 upon the secondary detent arm 137. This secondary detent arm 137 is pivoted upon the pivot stud 139 to a portion of the structure of the case. At the opposite end, the secondary detent arm 137 is provided with a spring stud 141 which holds one end of the tension coil spring 143. The other end of the coil spring 143 is anchored to the spring stud 145 fixed to a portion of the structure of the case. At the side of the notch 133, the secondary detent 127 is provided with an additional notch 147. To move the control knob 20 from the "simmer" position into any portion of the "high" position, the additional projection 123 must push the projection 125 out of the way. To do this, the notch 147 must be moved into a position receiving the complementary projection 135. This requires a force corresponding to the force required when the projections 80, 96 and 100 are moved to lift the roller 82.

The control knob 20 may be moved to any portion of the "high" position. There is no detent or stationing mechanism operative in any portion of the "high" position. As soon as the control knob is released, the operating shaft 24 will rotate in the counterclockwise direction under the force of the spring of the clock mechanism 56 which will regulate the movement at a uniform rate to make the time elapsed proportional to the time indicated upon the legends of the control knob 20. The spring of the clock mechanism of course is too weak to overcome a force corresponding to the force required to lift the roller 82 over one of the projections. Therefore in this return or counterclockwise movement any resistance to the movement of the control knob from the "high" to the "simmer" position other than that provided by the clock mechanism must be eliminated to insure the return of the mechanism from the "high" to the "simmer" position. This is accomplished by having the projection 123 force the projection 125 out of its path when the knob is turned from the "simmer" to the "high" position.

This is illustrated in Fig. 3 wherein the secondary detent 127 is shown in its second position to which it moved by the projection 123 when the control knob is moved to the "high" position. When the detent 127 is moved to this second position, the counterclockwise movement of the projection 123 will carry it into the notch 131 without any engagement with the projection 125. The rotation of the operating shaft

24 and the control knob 20 under the force of the spring of the clock mechanism 36 will continue until the projection 123 engages the projection 149 upon the far side of the notch 131. This engagement is made approximately at the same time that the projection 121 engages the roller knob 20 from the "simmer" to either the "low," "medium high" or "off" positions. Continuing the movement following the engagement, will cause the projection 123 to carry the projection 149 out of its path and in so doing will pivot the secondary detent 127 until the notch 133 is again engaged by the projection 135. This therefore removes the notch 149 from the path of the projection 123 so that when the control knob is later to be moved into the "simmer" position the projection 123 can again freely enter the notch 131 to engage the projection 125 upon the far side of the notch 131.

As is better shown in Fig. 4, the projections 80, 96 and 121 are made lesser in width than the projection 123. The purpose of this is to prevent interference between the projections 80, 96 and 121 with the secondary detent 127 and its projections 125 and 149 which would otherwise interfere in the position shown in Fig. 3. The projection 123, however, is made sufficiently wide that it does engage the secondary detent 127.

The structure of the case is shown in Fig. 4. The case 21 is made of a plastic electrical insulating material and contains a cavity receiving the clock mechanism 36 which is enclosed by a thin metal plate 151. The movable reed switch elements 42 and 48, and 52 and 58 are mounted upon opposite side walls of the case. The cams 28, 30, 32 and 34 are preferably formed from a single piece of plastic molded upon the shaft 24. A connector 153 connects the rear end of the cam piece with the clock mechanism 36. The entire detent mechanism is mounted between the detent plate 155 and the mounting bracket 157 which are fastened to the front face of the case 21. The pivot studs 129, 139 and 86 and the stop stud 92 and the spring stud 145, are all held within apertures provided in both the detent plate 155 and the mounting bracket 157. Suitable shoulders on each prevent any axial movement. The construction is inexpensive and reliable.

While the form of embodiment of the invention as herein disclosed, constitutes a preferred form, it is to be understood that other forms might be adopted, as may come within the scope of the claims which follow.

What is claimed is as follows:

1. A control including a movable shaft means, a control device operated by the operation of said shaft means, said shaft means being provided with a primary detent means having a projection, a pivoted rockable secondary detent means having two spaced projections, said spaced projections having sufficient length and spread to alternately present themselves at two different locations in the path of movement of the primary detent projection, and resilient holding means for said secondary detent means, said resilient holding means and said secondary detent means having cooperating means providing two holding stations for holding either of the spaced projections alternately in the path of movement of the projection of the primary detent means.

2. A control including a movable shaft means, a control device operated from a first control

position to a second control position at one predetermined point in the movement of the shaft means, said shaft means being provided with a primary detent means having a projection movable with the shaft means and having a fixed relationship to said predetermined point, a pivoted rockable secondary detent means having two spaced projections, said projections having sufficient length and spread to alternately present themselves at two different locations in the path of movement of the primary detent projection, said secondary detent means and one of its projections being so located relative to the primary detent means and its projection that their engagement takes place substantially at said predetermined point in the movement of the shaft means at which the control device is operated from one position to another.

3. A control including a movable shaft means, a control device operated from a first control position to a second control position at one predetermined point in the movement of the shaft means, said shaft means being provided with a primary detent means having a projection movable with the shaft means and having a fixed relationship to said predetermined point, a pivoted rockable secondary detent means having two spaced projections, said projections having sufficient length and spread to alternately present themselves at two different locations in the path of movement of the primary detent projection, said secondary detent means and one of its projections being so located relative to the primary detent means and its projection that their engagement takes place substantially at said predetermined point in the movement of the shaft means at which the control device is operated from one position to another, said shaft means being provided with manual manipulating means whereby it may be moved in one direction to engage and move said one secondary detent projection out of the path of said primary detent projection in coordination with the movement of the control device from the first position to the second, and timing drive means for moving the shaft means in the opposite direction at a timed rate of movement through a point at which the control device is operated from the second position to the first position and continuing until the primary detent projection engages the second secondary detent projection.

4. A control including a movable shaft means, a control device operated to three different control positions in three different positions of the shaft means, said shaft means being provided with a resilient primary detent means including a projection and notch arrangement synchronized with two of said three different positions of said shaft means, a rockable secondary detent means provided with a notch, said primary detent means being provided with an additional projection of sufficient length to extend into said notch, a resilient two position holding means for holding said secondary detent means in either of two holding positions in which opposite sides of said notch are presented for engagement by said additional projection, said additional projection being oriented relative to the shaft means and one of the holding positions of said notch so that its engagement with one side of the notch is synchronized with the arrival of the shaft in the third of the three different positions of the shaft means.

5. A control including a reversible rotatable

shaft means, a spring means for turning said shaft means in one direction, means for turning the shaft means in the opposite direction and winding up said spring means, said shaft means being provided with a projection, a rockable detent means having a pivoting axis parallel to and sufficiently near to said shaft means to be in the path of said projection, said detent means including a rockable member having a notch with shoulders upon opposite sides of the notch, said detent means also including a snap acting resilient holding means for resiliently holding said rockable member in either of two stations, said rockable member in one of said stations having the first of said shoulders out of the path of said projection and having the notch and the second shoulder in one location in the path of said projection for stopping said shaft means in a first location in one direction of rotation, said rockable member in the second

5 of said stations having the second of said shoulders out of the path of said projection and having the notch and the first shoulder in a second location in the path of said projection for stopping said shaft means in a second location in the opposite direction of rotation.
